[57] CLAIM

The ornamental design for a shoe upper, shown and described.

DESCRIPTION

FIG. 1 is a left side elevational view of a shoe upper showing my new design;

FIG. 2 is a right side elevational view thereof;

FIG. 3 is a top plan view thereof;

FIG. 4 is a front elevational view thereof; and,
FIG. 5 is a rear elevational view of a shoe upper showing of our new design.

The broken line showing of a shoe sole in the figures is environmental only and forms no part of the claimed design.
